UNITED STATES PATENT OFFICE

LOUIS G. FREEMAN, OF CINCINNATI, OHIO, ASSIGNOR TO THE LOUIS G. FREEMAN COMPANY, OF CINCINNATI, OHIO, A CORPORATION OF OHIO

SIDE TACK PULLER

Application filed May 4, 1929. Serial No. 360,539.

My present invention is an improved tack pulling machine for use in operating upon boots and shoes during their construction, and more particularly relates to a machine 5 of the type disclosed and described in my co-pending application, Serial No. 661,450, filed September 7th, 1923, of which the present application is a continuation in part.

A feature of the present invention consists in the provision of a large reservoir 10 of oil and means to supply the same to the driving shaft, moving parts and fork carrying bar. As such tack removing machines usually depend upon a reciprocating and 15 oscillating bar, it is practically impossible to provide a fixed and oil-tight bearing through which the bar runs, owing to the oscillatory path of movement requisite for the tack removing fork. I have, in the present machine, overcome this difficulty, and have provided means which will supply a 20 large amount of oil to the moving parts, and yet will prevent the same from being thrown out along the line of the oscillating 25 tack fork carrying bar and damaging the shoe. Preferably I employ a plurality of oil retaining means for this purpose, which will yet permit free movement of the oscillating bar, as explained. The provision of a 30 substantial oil supply in a machine of this kind is a distinct novelty and I wish to claim the same broadly. Other important advantages, details and novel combinations of parts will be hereinafter more fully pointed 35 out and claimed.

In the accompanying drawings illustrating the preferred embodiment of my invention:—

Fig. 1 is a side elevation of the upper portion 40 of the machine;

Fig. 2 is a fragmentary, vertical, sectional elevation on the line 2—2 of Fig. 1;

Fig. 3 is a similar view illustrating a modified form of the invention;

Fig. 4 is another similar view disclosing a 45 different modification; and

Fig. 5 is a fragmentary elevation in section showing a variation of the invention.

Referring to the drawings, 10 designates 50 a base or pedestal in the lower part of which

is rotatably mounted a shaft carrying a driving pulley (not shown), the shaft being driven from any suitable source of power. Formed integral with the base 10, or secured thereto in any suitable manner and 55 extending upwardly therefrom to any convenient height is a head 13, this head being hollow and having a portion 14 thereof extending upward and laterally with respect to the base or pedestal 10. Intermediate the 60 ends of the vertical portion of the head 13 is a partition 15 which forms the bottom of an oil chamber or reservoir 16 containing a body of oil or other lubricating fluid 17. Mounted on the side wall of the head 13 is a crank shaft 22 to which is affixed a pulley 23 having a belt groove 24, and passing over the pulley 23 and the driving pulley (not shown), is a driving belt 25 by means of which rotary motion is imparted to the 65 crank shaft 22. Secured to the crank shaft 22 is a balance 27. Guideways are formed in the interior of the head portion 14 in which is slidably mounted a puller bar 32 the rear end of which is connected to an eccentric crank 70 pin 36 on the end of crank shaft 22. This puller bar is guided in its movement by a pivot bar 42, and a pivot bar link 43, as 75 shown in Fig. 1.

As the crank shaft 22 rotates, the splash 80 pin 44 which is conveniently and adjustably mounted on the puller bar 32, or upon any other suitable moving part of the mechanism within the hollow portion 14, splashes a portion of the oil 17 out of the reservoir 16 and forward toward the front of the head 14, thus lubricating the puller bar 32 and the bearings in which the same slides, as well as lubricating 85 the pivot points of the pivot bar link 43.

Lubrication almost to the point of excess is necessary, due to the great speed at which the crank shaft 22 revolves, and therefore no matter how tight the bearings may be, some oil will work through and there is, therefore, 90 danger that the oil will fly out onto the shoes from which the tacks are being removed. To obviate this danger, I have provided a partition wall shown at 46, which I have found an efficient means for preventing leakage of 95 100

oil out through the front of the head portion 14.

As a further safeguard to prevent any oil that may work out on bar 32—especially the top and bottom faces thereof—from flying off and soiling the shoe being worked on, I place a guard 71 on the puller bar 32 at a point just outside the opening in the head through which the puller bar 32 passes.

10 The front end of the puller bar is provided with means securing the shank end of a tack fork 48 in adjustable position.

Secured to the forward end of the portion 14 in any suitable manner is a scuffing guard 62 in which works the tack fork 48, and this scuffing guard has formed integral therewith, a side wing 63 separated from the main portion by a heel which acts to protect the upper of a shoe being worked upon from damage by the tack fork travelling in its orbit. At the side of the scuffing guard 62 there is an extended side 64 having the dual function of holding down the upper next to the tack when pulling tacks that are driven deep, 20 while enabling the operator to bring the shoe into operative position with respect to the tack fork quickly and without risk of the shoe slipping from its position and becoming damaged.

30 The operation of my improved device is as follows, it being assumed that such device is constructed and assembled in the manner above described. The reservoir 16 being filled with oil 17 to the desired depth so as to 35 allow the splash pin 44 to dip into the same and splash oil, the tack fork 48 and the scuffing guard 62 being adjusted to operate to remove tacks from the shoes, power is thrown onto the main shaft which, through the belt 40 25, imparts rotary motion to the crank shaft 22 and the crank 36 thereon will cause a reciprocatory motion of the puller bar 32. The reciprocatory motion imparted to the puller bar 32 is modified by means of the pivot bar 45 link 43 and the forward end of the puller bar is forced to describe an orbital path. The tack pulling operation is performed in the usual manner, the operator passing the shoe on the last transversely of the line of 50 travel of the tack puller 48, and the rapidly moving tack fork engaging with the tacks pulls them out of the shoe. The side wing 63 prevents injury to the shoe by the tack fork and the extended side 64 holds down the upper next to the tack, when pulling tacks, and enables the operator to bring the shoe into 55 operative position without risk of slipping from position and damaging the shoe, while the heel of the guard holds the upper down 60 on the last while the tacks are being pulled.

The scuffing guard as a whole prevents scuffing of the shoe uppers by the tack fork 48. The partition wall 46 prevents oil working out of the head 14 and flying onto the shoe.

65 The oil supply is preferably sufficient to

last an entire month thus insuring the continued efficiency of the machine without stopping for oiling or endangering the machine through careless operators who neglect to oil all moving parts when needed.

70 The construction illustrated in Figs. 1 and 2 describes particularly the use of a splash pin adjustably engaging someone of the moving parts of the tack pulling mechanism, and effective to dip into the oil regardless of its level. Obviously this adjustable pin 44 might be mounted on the counter-balance 27, or for that matter the puller bar or counter-balance or other moving parts might themselves dip into the oil if the level is sufficiently 75 high.

80 The splashing may readily be accomplished, however, by various constructions and in Fig. 3, there is illustrated a splash wheel 75 which is mounted for movement independent of the actuating mechanism on a stub shaft 76, projecting through the head portion 13, a pulley 77 on the outer end of this stub shaft provides a means of driving the paddle wheel 75 from the main driving shaft 90 for the machine. The paddle wheel 75 can be made of any shape desirable, and can extend into the surface of the oil any required depth. Furthermore, it may be driven in either direction by using either a straight or cross belt 95 connection to the main driving shaft, and by changing the size of the pulley any desired speed or R. P. M. of the wheel may be obtained.

100 In Fig. 4 a variation of the structure shown in Fig. 3 is illustrated, and in which the paddle wheel 75 has its buckets 78 transversely extended toward the puller bar. Obviously, oil will be lifted by the buckets 78 as they 105 dip into the oil, to be thrown or dropped upon the puller bar and associated mechanism as the wheel rotates.

110 Fig. 5 also shows a form of lubricator in which the operating mechanism is entirely independent of the actuating mechanism of the tack pulling machine. In this figure is disclosed an oil pump 79 driven by a pulley 80 to force air through a nozzle 81, which nozzle is directed against the actuating mechanism. Air in being forced up through the pipe draws oil from the reservoir and sprays or splashes same on the actuating mechanism of the tack puller.

115 While I have necessarily shown and described the preferred embodiment of my invention, somewhat in detail it is to be understood that I may vary the size, shape and arrangement of parts comprising the invention within wide limits without departing from the spirit of the invention.

120 The large oil supply insures the running of the machine, and permits greatly increased speed of operation, with perfect safety and efficiency, and yet while supplying for this purpose a large volume of oil, protects and 125

guards the shoe from damage by escape of oil.

Having thus described my invention, what I claim as new and desire to secure by Letters Patent of the United States, is:—

5 1. A tack pulling machine having in combination, tack pulling means and actuating mechanism therefor, a casing forming an oil reservoir, and enclosing said mechanism, means to splash oil over said actuating mechanism during operation thereof, thereby to bathe the same in oil, and means to prevent the oil thus splashed from reaching the work.

10 2. A tack pulling machine having in combination, tack pulling means and actuating mechanism therefor, a casing forming an oil reservoir and enclosing said mechanism, means in said casing to splash oil within the casing, thereby to bathe the actuating mechanism in oil, said machine being constructed and arranged to prevent the oil splashed over the actuating mechanism from reaching the work.

15 3. A tack pulling machine having in combination tack pulling means and actuating mechanism therefor, including a puller bar, work guarding means adjacent a portion of the path of movement of said tack pulling means, a casing forming an oil reservoir and enclosing said actuating means, said puller bar being reciprocable in said casing, means adjacent the puller bar to splash oil over said mechanism thereby to bathe the same in oil, and means to prevent the oil thus splashed from reaching the work and work guarding 20 means.

25 4. A tack pulling machine having in combination, a tack pulling means and actuating mechanism therefor, a casing forming an oil reservoir and enclosing said actuating mechanism, and means to splash oil over said actuating mechanism thereby to bathe the same in oil, said casing having a partition wall to prevent oil from escaping to the work.

30 5. A tack pulling machine having in combination tack pulling means and actuating mechanism therefor, including a puller bar, a casing forming an oil reservoir and enclosing the major portion of said bar, said puller bar being movable in said casing, and means to splash oil within the casing thereby to bathe the puller bar and associated mechanism in oil, and a guard on the puller bar to prevent oil from creeping along the bar to the work.

35 6. A tack pulling machine having in combination, tack pulling means and actuating mechanism therefor, a casing forming an oil reservoir, and enclosing said mechanism, a driven member independent of said actuating mechanism effective to splash oil over said actuating mechanism during operation thereof, thereby to bathe the same in oil, and means to prevent the oil thus splashed from reaching the work.

40 7. A tack pulling machine having in com-

bination, tack pulling means and actuating mechanism therefor, a casing forming an oil reservoir and enclosing said mechanism, a member driven independently of said actuating mechanism effective to splash oil over said actuating mechanism during operation thereof, thereby to bathe the same in oil, said machine being constructed and arranged to prevent the oil splashed within the casing from reaching the work.

75 8. A tack pulling machine, having in combination tack pulling means and actuating mechanism therefor, a casing forming an oil reservoir, and enclosing said mechanism, a splash wheel independent of said actuating mechanism effective to splash oil over said actuating mechanism during operation thereof, thereby to bathe the same in oil, and means to prevent the oil thus splashed from reaching the work, and means to drive said actuating mechanism and said splash wheel from a common source of power.

80 9. A tack pulling machine having in combination, tack pulling means and actuating mechanism therefor, a casing forming an oil reservoir and enclosing said mechanism, a splash wheel independent of said actuating mechanism effective to splash oil over said actuating mechanism during operation thereof thereby to bathe the same in oil, said machine 90 being constructed and arranged to prevent the oil splashed within the casing from reaching the work, and means to drive said actuating mechanism and said splash wheel from a common source of power.

95 In testimony whereof I hereunto affix my signature.
